UNITED STATES PATENT OFFICE.

ROBERT A. COURTNEY, OF BALTIMORE, MARYLAND.

DESIGN FOR A DISPENSING DEVICE.

47,948.

Specification for Design.

Patented Oct. 12, 1915.

Application filed May 21, 1915. Serial No. 29,672. Term of patent 3½ years.

To all whom it may concern:

Be it known that I, ROBERT A. COURTNEY, a citizen of the United States, residing at Baltimore, State of Maryland, have invented a new, original, and ornamental Design for Dispensing Devices, of which the following is a specification, reference being had to the accompanying drawing, forming part thereof.

The figure is a perspective view of the dispensing device showing my new design.

I claim:

The ornamental design for a dispensing device, as shown.

ROBERT A. COURTNEY.

Witnesses:

FLORENCE M. RICHTER,
PETER J. CAMPBELL.
